UNITED STATES PATENT OFFICE.

FRANK C. MOCK, OF CHICAGO, ILLINOIS, ASSIGNOR TO STROMBERG MOTOR DEVICES CO., A CORPORATION OF ILLINOIS.

FUEL VAPORIZER.

Application filed October 21, 1922. Serial No. 595,899.

To all whom it may concern:

Be it known that I, FRANK C. Mock, a citizen of the United States, residing at Chicago, in the county of Cook and State 5 of Illinois, have invented a certain new and useful Improvement in Fuel Vaporizers, of which the following is a full, clear, concise, and exact description, reference being had to the accompanying drawings, 10 forming a part of this specification.

The present invention relates to fuel vaporizers for internal combustion engines.

One of the principal objects of my invention is to provide an improved method 15 of and means for separating the unvaporized or unfogged fuel from the mixture charge for subjection to a source of heat. This improved method of separation operates upon the theory of a change in direction 20 of the mixture stream and a reduction in velocity thereof. A single right angle turn, or even a lesser deflection of the mixture stream will separate practically all of the unvaporized or unfogged fuel from the 25 charge when the velocity of the charge is held down to a sufficiently low speed. By reducing the velocity of the mixture stream in this manner, the fuel particles which have been separated from the mixture 30 stream will not be wiped or dragged along the walls of the manifold into the valve pockets and engine cylinders. By keeping the air velocity sufficiently low just beyond this point of fuel separation, the separated 35 liquid fuel can be made to assume a gravitational flow down an inclined surface in a direction counter to the air stream. I utilize this gravitational flow to distribute the separated fuel in a thin liquid film over 40 a large area of heating surface; and also to return any fuel which has not been vaporized by the foregoing subjection to heat back to a point of high air velocity, whereby 45 this fuel can be again introduced into the air stream for atomization or a subsequent subjection to heat.

Experiments have indicated that under 50 conditions where the air velocity is less than approximately 30 feet per second, the fuel once separated, will cling to the heated vaporizing surface and drain, by the action of gravity to the lowest part of the system. Inasmuch as the velocity of discharge from

the average carburetor at high motor speed may attain speed as high as approximately 55 250 feet per second, it will be apparent that a very considerable reduction in air velocity at the point of fuel separation is necessary for the effective performance of the foregoing method. This reduction in velocity 60 is obtained by causing a very considerable enlargement of the mixture stream. I have found that the mere introduction of a mixture stream into an enlarged passage is generally not enough to slow down the entire 65 sectional area of the mixture stream, as the central part of the mixture stream will exist as a high velocity stream filling only a portion of the passage, the outer strata of the stream perhaps expanding and falling off 70 in velocity. Accordingly, I find it desirable to provide means for mechanically diffusing or spreading the stream over substantially 75 the entire area of the enlarged fuel separating chamber, this being accomplished by deflecting baffles or the like interposed in the path of the mixture stream.

After the unvaporized or unfogged fuel has been separated from the mixture stream 80 it must be retained on the heated surface 80 in a comparatively thin film, distributed over a large area, until evaporation is completed. If the temperature of the heating surface is somewhat above the boiling point 85 of the fuel, this evaporation will result from the plain boiling of the fuel. If the temperature of this heating surface is much in excess of the boiling point of the fuel, the fuel may evaporate in spheroidal condition, 90 that is to say, it will bounce off the heating surface in drops and evaporate. If the temperature of the heating surface falls below the boiling point of the fuel, the fuel will only evaporate by surface evaporation. 95 For rapid surface evaporation it is highly important that the fuel be distributed in a film over as large a surface as possible, otherwise there will be a tendency for the fuel to collect and "load" when the rate of 100 fuel supply from the carburetor exceeds the rate of evaporation.

The invention is further characterized by the provision of an improved arrangement of ribs for collecting the heat from the exhaust gases, also an arrangement of ribs on 105 the surface of the vaporizing plate which,

- in effect, form distributing dams, to insure that the fuel will be compelled to cover a large area of surface rather than being allowed to collect in one spot.
- Referring to the accompanying drawings illustrating a preferred embodiment of my invention:
- Figure 1 is a longitudinal sectional view through the fuel vaporizer;
- 10 Fig. 2 is an inverted sectional view of the same taken on the plane of the line 2—2 of Fig. 2;
- Fig. 3 is a horizontal plan view taken approximately on the plane of the line 3—3 of Fig. 1;
- 15 Fig. 4 is an inverted view taken approximately on the plane of the line 4—4 of Fig. 1;
- Fig. 5 is a plan view of a modified construction;
- Fig. 6 is a longitudinal sectional view through the same;
- Fig. 7 is a detail view of the pivoted spreading baffle;
- 20 Fig. 8 is a diagrammatic illustration of dash control connections associated with the foregoing construction;
- Fig. 9 is an elevational view of the control buttons;
- 25 Fig. 10 is a vertical sectional view of a modified construction; and
- Fig. 11 is a transverse sectional view taken on the plane of the line 11—11 of the above figure.
- 30 Referring to Figs. 1 and 2, the vaporizer comprises a three sided casing 14 which extends upwardly at a slight incline and has an open bottom for the reception of the vaporizing plate 17. The outline of this casing 14 is substantially as shown in Fig. 2, and the lower end of the casing has an inlet 18 formed with a connecting flange 19, to which is bolted the conventional manifold flange of a horizontal type of carburetor 21.
- 35 The upper end of the casing 14 is formed with an upwardly extending conduit 22 which may be flanged or otherwise adapted for connection with the usual intake manifold. The lower margin of the casing 14 is provided with a flange 23, from which is supported the vaporizing plate 17 and the exhaust casing 24. The vaporizing plate 17 is of the same outline as the open bottom of the casing 14, and this plate has a dropped flange 25 which is adapted to be secured to the flange 23. A comparatively thick gasket 26 of heat insulating material is interposed between the flanges 23 and 25, so that the heat which is imparted to the vaporizing plate 17 will not be transmitted to the casing 14.
- 40 The exhaust casing 24 has an inlet connection 27 into which fits the inlet exhaust conduit 28. A gland and packing 29 may be provided for sealing the connection between the conduit 28 and the inlet 27. The inlet is preferably at the upper end of the exhaust casing so that the exhaust gases will impinge on the reverse side of the vaporizing plate 17, and will be forced to flow 70 downwardly along said plate to the outlet 31. An outlet conduit 32 leading from this outlet connection 31 may be provided with a similar packing 33. The entire volume of exhaust gases may be circulated through 75 the casing 24, or only a part thereof shunted through this casing. In the latter case, any suitable manual or automatic control may be provided for regulating the volume of exhaust gases thus shunted through the casing 80 24.
- 45 A very large surface for heat absorption is provided by forming depending ribs 34 on the under side of the vaporizing plate 17. As shown in Fig. 4, these ribs are arranged 85 in rows extending transversely of the flow of the exhaust gases. It will be observed that these ribs flare outwardly from each side of the center of the exhaust chamber, and it will also be observed that the diagonal disposal of these ribs is reversed in each successive row, this arrangement having the action of bringing a different layer of exhaust gas in contact with each subsequent row of ribs.
- 50 Referring now to Fig. 2, the mixture stream is deflected outwardly into the greater area of the casing 14 by the diverging deflecting ribs 36 depending from the inclined top of the casing 14. The leading edges of these ribs 36 are grouped in close proximity to the inlet 18, and their trailing ends diverge outwardly toward the outer walls of the casing so as to forcibly turn portions of the mixture stream outwardly 100 into the outer confines of the casing. This has the action of lowering the velocity of the mixture stream by the mechanical diffusion thereof, so that the lower velocity flow of the mixture stream will drop the unfogged particles of fuel, and will not wipe up particles of fuel from the vaporizing plate 17 nor sweep any accumulation of fuel upwardly through the outlet 22. As shown in Fig. 3, the surface of the plate 17 is ribbed by a plurality of transverse ribs 37, which incline downwardly from the center toward the sides of the plate at a slight angle. A groove 38 is extended around the margins of the plate 17 adjacent the casing wall 14, and the small gutter formed in the front of each rib 37 discharges into this groove 38. Consequently, any accumulations of fuel which do not vaporize under the heat of the plate 17 and the reduced pressure prevailing in the vaporizing chamber are conducted laterally to the trough or groove 38 where they flow downwardly into the area 39 in the bottom of the casing 14. As before stated, the car- 105 110 115 120 125 130

bureter 21 is preferably of the horizontal type, and is preferably arranged with the shaft 41 of its throttle 42 extending horizontally. By this arrangement, when the engine is running on restricted throttle, a very high velocity stream of air will be drawn above the upper lip of the throttle, and below the lower lip of the throttle, which high velocity stream of air will pick up accumulations of fuel in the area 39 and reatomize the same or carry such fuel upwardly through the vaporizing chamber for a repetition of the foregoing cycle.

By virtue of the heat insulating gasket 26 a minimum amount of heat is transmitted to the casing 14, and by forming the rib 36 to depend from the top of the casing 14, a negligible amount of heat is conducted to these ribs. Consequently, the transmission of heat to the air component of the charge is reduced as much as possible. The diverging ribs 36 also function to collect accumulations of liquid fuel and to deflect these accumulations outwardly towards the sides 25 of the casing, the fuel running along these ribs until the decrease of air velocity ceases to carry them, when they drop down on the vaporizing plate 17. The flow of air tends to distribute accumulated fuel upwardly over the vaporizing plate 17, and gravity tends to cause the fuel to flow downwardly, whereby a wide spread distribution of the fuel is obtained across the entire surface of the vaporizing plate 17.

In Figs. 5 and 6 the mixture stream is led into the upper part of the vaporizing chamber 14' through the inlet 18', the vaporizing plate 17' being disposed below the level of the inlet opening 18'. The outlet 22' is substantially in line with the inlet 18'. As will be noted from Fig. 5, the chamber 14' is expanded laterally to a considerable degree to provide an extensive area of vaporizing chamber for reducing the velocity of the mixture stream. Normally, it will be apparent that considerable part of the mixture stream would pass direct from the inlet 18' to the outlet 22' without any great reduction in velocity and without opportunity for precipitating unfogged fuel particles on the vaporizing plate 17'. To prevent this direct passage of the mixture stream there is provided a swinging baffle 44 which is pivoted in the upper part of the casing 14' on a pivot shaft 45. This baffle is positioned to swing down or up, into or out of line with the blast of the mixture stream entering the inlet 18'. When in its lowered position, as indicated in full lines, it has the action of deflecting the mixture stream downwardly and outwardly to expand the stream throughout the entire vaporizing chamber so as to obtain the desired reduction in velocity. As will be noticed in Fig. 7, the baffle 44 is

arched or formed of V configuration so as to divide the mixture stream and deflect the same laterally towards the sides of the vaporizing chamber. The lower edge of the vaporizing chamber 14' is flanged for 70 securing the exhaust casing 24' and the vaporizing plate 17' thereto, a heat insulating gasket 46 being interposed between the vaporizing plate 17' and the casing 14' as in the preceding embodiment. The plate 17' is formed with a plurality of heat absorbing ribs 47 which extend downwardly into the exhaust casing 24'. As shown in Fig. 5, these ribs are disposed in successive rows transversely to the passage of the exhaust gases, the ribs being diverged diagonally from the center in alternating directions, substantially as described in the preceding form. The exhaust gases are conducted into the exhaust casing 24' at 28' and are discharged from this casing through the outlet conduit 32'.

If desired, a tube 48 may be extended between the lower part of the vaporizing chamber 14' and the venturi of the carburetor, or any point of high suction, so as to provide a passageway for drawing any accumulations of unvaporized fuel from the surface of the vaporizing plate 17' up into the carburetor or carbureting passageway 95 for a subsequent introduction into the air stream.

It is common practice to extend the intake manifold of the engine through the water jacket space 51, as shown as 52. When operated alone, this method of vaporizing the fuel particles is frequently inadequate in cold weather, and, to take care of this condition, exhaust heated vaporizers, such as the vaporizing chamber 14', are 100 sometimes provided to assist in the complete vaporization of the fuel in cold weather. In hot weather, this duplex arrangement of vaporizer frequently tends to overheat the mixture, resulting in detonation and a reduced density of charge. I have found that by controlling the percentage of fuel thrown on the vaporizing surface the final temperature of the mixture can be regulated through a wide range, so as to take care of these 110 conditions. This action follows from the fact that in the present method of fuel vaporization the fuel content acts as an effective heat conducting medium between the vaporizing surface and the remaining body 115 of the mixture. The fuel comes into much more intimate contact with the vaporizing surface than does the air; demonstrations showing that a much greater amount of heat is extracted from the vaporizing surface 120 when the fuel of the mixture is thrown upon the vaporizing surface than when the air content alone of the mixture is passed over the surface. I utilize this heating characteristic of the fuel by pivotally mounting 125

the deflecting baffle 44 on a pivot shaft 45 so that the quality of fuel thrown down on the vaporizing surface can be controlled, and thereby the resulting temperature of the mixture controlled.

When the baffle 44 is swung up into its dotted line position the section 52 of the intake manifold is relied upon for vaporizing those fuel particles which are sustained in the mixture stream.

It should be remarked at this point that the vaporizing chamber 14' has a gravitational separating action which functions automatically in accordance with the engine speed. A complete and thorough vaporization of all unfogged fuel particles is not necessary at high motor speeds, because at such speeds the cylinder temperature is sufficiently high to vaporize the fuel particles; and equal distribution of the fuel between the several cylinders is assured by the comparatively high air velocities, which convey the fuel to the endmost points of the manifold. It is at the low motor speeds that a high degree of external fuel vaporization is desired, because of the lower cylinder temperatures and because of the inability of the lower air velocities to equally distribute the fuel particles between the cylinders. At these low motor speeds the unfogged fuel is dragged along the walls of the mixture passageway by the air stream. It will be noted that in the present embodiment such fuel that is dragged along the walls of the carburetor 21' and intake 18' is precipitated down on the vaporizing plate 17' irrespective of the position of the baffle 44. Consequently, a fuel vaporizing action always occurs automatically when the air velocity drops to that point at which it is desirable to have vaporization occur. Vaporization at the high motor speeds is made more or less dependent on the position of the baffle 44.

The position of the baffle 44 may be made dependent upon the position of the throttle 42, by connecting a link 81 between arms 82 and 83 mounted on the throttle shaft 41 and baffle shaft 45, respectively.

As an alternative arrangement, the baffle 44 may have a separate dash control, as shown in Figure 8, in which the baffle has operative connection with a control button 55 on the dash 54. An operating rod 56 extends down from the button 55, and has any suitable operative connection with the pivot shaft 45, as through the instrumentality of the crank arm 57 and the two bevel gears 58 and 59. A second control button 61 is also provided on the dash in proximity to the vaporizer control button 55. The button 61 has connection through a rod 62 with the crank arm 63 of a choker valve 64 disposed in the air intake of the carburetor 21'. As shown in Fig. 9, the choke button 61 had rigidly secured thereto

an arm 65 which extends down under the flange of the heat button 55, the lower end of this arm being notched out to embrace the hub of the button 55. By slightly rotating the button 61 the arm 65 can be made to clear the button 55 so that each button may be operated independently of the other. In summer, when the engine is to be started, the "choke" button 61 is pulled outwardly, and this button acting through the arm 65, pulls the "heat" button 55 outwardly, so that for starting a rich mixture is secured and this mixture is deflected down into the vaporizing chamber 14' for vaporization of the fuel particles therein. After the motor has been running a short time, the "heat" button is pushed inwardly, which operates to open the choke valve 64 and raise the deflecting baffle 44. For winter driving, the "heat" button is left out all the time so as to place the heat baffle 44 in its downward deflecting position, and the "choke" button is operated in and out independently of the "heat" button.

In Figures 10 and 11 the vaporizing chamber is illustrated as extending substantially at right angles to the incoming charge of mixture from the carburetor 21. The carburetor is illustrated as being of the horizontal type, and the vaporizing chamber 68 extends substantially upright alongside of the motor block. The inlet 69 enters the bottom of the chamber 68, and the outlet 71 discharges from the upper end of the chamber 68, preferably at a point adjacent to the front wall of the chamber so that there will be a minimum possibility of fuel being drawn upwardly along the vaporizing plate 72 and into the outlet 71. An insulating gasket 72 is interposed between the vaporizing plate 72 and the vaporizing chamber 68, and an exhaust casing 74 is bolted to the back of the vaporizing plate 72 for circulating the exhaust gases into contact therewith. This exhaust casing has exhaust inlet connection 75 and outlet connection 76, and this exhaust casing houses a plurality of heat absorbing lugs or ribs projecting from the back of the vaporizing plate 72.

The mixture stream entering through the inlet 69 impinges upon a V-shaped dividing rib 77 which is disposed more or less obliquely to the entering stream. This dividing rib spreads out the high velocity part of the mixture stream to the side areas of the vaporizing chamber 68, with the effect that the unvaporized fuel particles impinge on the vaporizing plate 72 and rib 77, and are spattered or washed diagonally upward and sidewise. These fuel particles are either vaporized by the heat of the plate 72 or they finally reach side walls of the vaporizing chamber, from whence they drain back to the mixture inlet 69 and the carburetor

mouth. From this point such unvaporized fuel is again thrown up on the heating surface. The lateral enlargement of the mixture stream into the greater width of the vaporizing chamber 68 reduces the velocity of the mixture stream to a point where it will no longer sustain the fuel drops. Adequate surface necessary for conditions of surface evaporation is obtained by virtue of the fact that when the motor is idling there is a very high velocity through the throttle crack and this velocity washes the liquid fuel up on the dividing rib and keeps it spread out well in a liquid film.

15 I claim:

1. In combination, a fuel vaporizing chamber, an inlet mixture conduit entering said chamber, said chamber being enlarged laterally to each side of the point of entrance of said conduit, a baffle encountered by the mixture stream entering through said conduit and operable to divide the mixture stream and spread the same laterally to each side from said inlet conduit, thereby changing the direction of flow of said mixture stream and reducing its velocity in the expanded area of said vaporizing chamber, a vaporizing plate positioned to receive the fuel particles precipitated by said reduction in velocity and change of direction, an outlet removed from said vaporizing plate and adapted to be connected with the intake manifold, a shoulder interposed between said mixture outlet and said vaporizing surface at an angle to the latter for preventing fuel particles from being swept out through said outlet, an exhaust casing enclosing the reverse side of said vaporizing plate, heat absorbing ribs projecting from said vaporizing plate into said exhaust casing, and conduit means for circulating exhaust gases through said exhaust casing.

2. In combination, an intake manifold, a carburetor, fuel vaporizing means interposed therebetween comprising a fuel vaporizing chamber having outlet and inlet conduits adapted for connection with said manifold and said carburetor respectively, means in said chamber for spreading the entering mixture stream into the enlarged area of said chamber and thereby reducing its velocity, a heated vaporizing plate disposed at an angle to the entering mixture stream, said mixture inlet discharging substantially horizontally into said chamber and entering the bottom thereof whereby fuel particles not vaporized on said vaporizing plate will gravitate down along the walls of said chamber towards said mixture inlet where they will be subjected to the high velocity portion of the entering mixture stream.

3. In fuel vaporizing means of the class described, the combination of a vaporizing

chamber, a vaporizing plate in said chamber inclined toward said inlet, and means on said plate for distributing the accumulations of liquid thereon.

4. In fuel vaporizing means of the class described, the combination of a vaporizing chamber having a mixture inlet and a mixture outlet, a heated vaporizing plate in said chamber inclined downwardly toward the inlet, and shoulders associated with said plate for damming the surface flow on said plate.

5. In fuel vaporizing means of the class described, the combination of a vaporizing chamber having a horizontal mixture inlet adapted for connection with a carburetor, and an upwardly extending mixture outlet adapted for connection with an intake manifold, a heated vaporizing plate in said chamber inclined to be impinged against by the entering mixture stream, and ribs formed on the surface of said vaporizing plate for damming the surface flow and distributing the liquid fuel over said vaporizing plate.

6. In fuel vaporizing means of the class described, the combination of a vaporizing chamber having a mixture inlet and a mixture outlet, an inclined heated vaporizing plate disposed at an angle to the entering mixture stream, and transverse channels associated with said vaporizing plate for damming the surface flow thereof, and a longitudinal channel associated with said plate for conducting the surface flow from said transverse channels back to said mixture inlet.

7. In combination, a vaporizing chamber having an inlet at one end and an outlet at the other end, said chamber between said inlet and outlet being expanded laterally, one wall of said chamber forming a hot surface, and baffle members extending between said inlet and outlet and arranged to guide a fuel mixture in divergent paths from said inlet to the outlet, whereby said mixture will be gradually spread through said chamber and into contact with said hot surface.

8. In combination, a vaporizing chamber having an inlet for fuel mixture and an outlet, said chamber between said inlet and outlet being of gradually increasing cross sectional area, the bottom of said chamber forming a hot plate, and baffle members extending from said inlet for receiving said fuel mixture and conducting it in divergent paths to spread it uniformly through said chamber and over said hot plate.

9. A vaporizer having a chamber, a fuel mixture inlet at one end and an outlet at the other end, a vaporizing surface positioned in said chamber to be impinged against by the inflowing mixture, and guide walls within said chamber receiving the mixture at said inlet and causing it to flow

in laterally divergent paths and into engagement with said vaporizing surface.

10. In combination, a vaporizing chamber having a fuel mixture inlet at one end and an outlet at the other end, said chamber between said inlet and outlet being enlarged laterally whereby to permit expansion of the mixture flowing therethrough, a vaporizing surface on the bottom of said chamber, and baf-

15
fle walls extending from said inlet towards said outlet, said walls being positioned to separate the incoming mixture into streams and for directing such streams laterally and against said vaporizing surface before said outlet is reached.

In witness whereof, I hereunto subscribe my name this 16th day of October, 1922.

FRANK C. MOCK.
